200,744

AIRCRAFT

John J. Grebe, 1505 W. Saint Andrews Drive,
Midland, Mich.

Filed May 9, 1963, Ser. No. 74,831

Term of patent 14 years

(Cl. D71—1)

FIGURE 1 is a top plan view of an aircraft showing my new design wherein the rudder configuration is in folded, closed position on the fuselage;

FIGURE 2 is a side elevational view thereof with the rudder configuration in upright, vertical position;

FIGURE 3 is a front elevational view thereof with the rudder members extended at an outward angle;

FIGURE 4 is a rear elevational view thereof with the rudder members in an unfolded dove-tail position;

FIGURE 5 is a top plan view of the design shown in FIGURES 1-4 with one of the rudder members in folded position on the fuselage and the other in outwardly extended position;

FIGURE 6 is a rear elevational view of the rudder configuration depicted in FIGURE 5;

FIGURE 7 is a fragmentary side elevation view of the rudder configuration depicted in FIGURE 4.

The dominant features of this design reside in the rudder members shown in full lines on the drawings.

I claim:

The ornamental design for an aircraft, as shown and described.
